UNITED STATES PATENT OFFICE.

BALTHASAR KREISCHER, OF NEW YORK, N. Y.

DESIGN FOR FILLING-IN TILE.

Specification forming part of Design No. 5,186, dated August 8, 1871.

To all whom it may concern:

Be it known that I, BALTHASAR KREISCHER, of the city, county, and State of New York, have invented a new and original Design for Filling-in Tile; and I do hereby declare the following to be a full, clear, and exact description thereof, which will enable those skilled in the art to make and use the same, reference being had to the accompanying drawing forming part of this specification, in which—

Figure 1 represents a transverse section of my filling-in tile. Fig. 2 is a side view of the same.

Similar letters indicate corresponding parts.

This design relates to a tile with a slightly-arched top, joined by rounded corners to short vertical sides, leaving an open bottom, in such a manner that when the tile is inserted between two beams its vertical sides fit closely to the sides of the beams, while the arched top forms the support for the floor between the two beams, and by these means a cheap, light, and durable filling-in is obtained.

In the drawing, A designates a tile formed with an arched top, *a*, rounded corners *b*, and short vertical sides *c*, leaving an open bottom.

The tile is made to fit nicely between two beams, to the inner surface of which are nailed suitable strips of wood to support the tiles, said supporting-strips being so situated that the upper surfaces of the tiles are level, or nearly so, with the upper surfaces of the beams. The ordinary filling-in boards can therefore be dispensed with, and my tiles serve to support the floor between the beams.

What I claim as new, and desire to secure by Letters Patent, is—

The design for a filling-in tile, as herein shown and described.

B. KREISCHER.
